SEWING MACHINE

Walter Pearson, Whitman, Mass.

Application September 9, 1933, Serial No. 688,806

11 Claims. (Cl. 112—34)

My invention relates to sewing machines, especially McKay sewing machines, and it has for its object to improve the construction and operation of sewing machines of this class.

5 To this end I have provided an improved sewing machine of the class indicated having the peculiar features of construction and mode of operation set forth in the following description, the several novel features of the invention being 10 separately pointed out and defined in the claims at the close thereof.

In the accompanying drawings:

Figure 1 is a front elevation of the head of my improved sewing machine.

15 Figure 2 is a detail, partly in elevation and partly in section, of the needle bar and cast-off.

Figure 3 is a section on line 3—3 of Fig. 2.

Figure 4 is a section on line 4—4 of Fig. 1.

20 Figure 5 is a detail, in plan, of the work guide hereinafter referred to.

Figure 6 is a section on line 6—6 of Fig. 4.

Figure 7 is a front elevation of a portion of the sewing mechanism showing the work in position upon the horn or workrest of the machine.

25 Figure 8 shows, in elevation, the needle-bar mechanism and part of the cast-off mechanism.

Figure 9 shows, in elevation, the presser-foot mechanism and part of the cast-off mechanism.

The illustrated embodiment of my invention 30 comprises a head frame 10 which, as usual, is fixed in position upon the upper end of a column or post (not shown) having a base that is seated upon, and usually secured to, the floor. Frame 10 is a box-like structure having a horizontal top wall, two oppositely disposed vertical side walls and a horizontal bottom wall. Removably secured to the front of this frame is a closure plate 10a. Most of the operating parts of the sewing mechanism are housed within this frame 10.

40 The needle mechanism comprises a needle-bar 11 slidable vertically in bearings provided in the top and bottom walls of frame 10. Fast on needle-bar 11 is a collar 12 made at its front with an upstanding apertured lug or ear 45 13 disposed between the apertured arms of a fork or yoke provided at the forward end of a lever 14. A pintle 15 pivotally connects the said arms to the lug or ear 13.

50 Intermediate its ends the lever 14 is made with a longitudinally disposed arcuate slot 16, Fig. 8, within which is slidably mounted an apertured arcuate fulcrum block 17 that is connected by a fulcrum pintle 18 with a support 19 herein shown as an angularly adjustable arm

secured to a rockshaft 20 journaled in bearings provided on frame 10.

The upper end of arm 19 is forked and embraces both the lever 14 and fulcrum block 17.

5 The rear end portion of the lever 14 is also forked to provide a straight longitudinal slot 21 that is occupied by a triangular cam 22 fast on the main or prime power shaft 23 of the machine, and as said shaft and cam rotate in the direction of the arrow the latter vibrates lever 14 on 10 the axis of fulcrum pintle 18 and said lever acts through pintle 15 and collar 12 to reciprocate needle-bar 11 vertically.

Owing to the triangular shape and design of the cam 22 the lever 14 is caused to dwell motionless for a period of time at each end of its stroke, and consequently the needle-bar 11 dwells correspondingly at each end of its stroke.

20 In Fig. 8 the parts are shown in the positions they occupy at the moment the needle-bar arrives at the limit of its downward movement and the needle-bar remains stationary in this lowermost position while shaft 23 rotates sixty degrees from the position shown. During this dwell the whirl or looper (not shown) that is 25 within the horn 24, Fig. 7, lays the thread around the needle 25 of needle-bar 11.

Then, during the next one hundred and twenty degrees of movement of shaft 23, the lever 14 is swung on its fulcrum so as to raise the needle-bar to the limit of its upward movement where it dwells while shaft 23 rotates sixty degrees more.

30 Thereafter, additional rotation of shaft 23 to the extent of one hundred and twenty degrees 35 restores the parts to the positions shown in Fig. 8 with the needle-bar 11 at the limit of its downward movement which completes the cycle of the machine.

The arcuate slot 16 of lever 14 is concentric 40 with the axis of rock shaft 20 when the needle-bar 11 occupies its lowermost position at which time its needle 25 is within horn 24. Therefore, it will be clear that the only effect of angular adjustment of the fulcrum arm 19 is to vary 45 the extent of upward movement of the needle-bar without change in the position of the needle when the needle-bar occupies its lowermost position whatever may be the position of the fulcrum arm 19.

50 It is a feature of this invention that the fulcrum arm 19 is automatically controlled and angularly adjusted and positioned by the presser-foot mechanism, presently to be described, thereby to vary the stroke of the needle-bar accord-

- ing to the thickness of the work as gauged or determined by the presser-foot mechanism in co-operation with the usual work-supporting horn 24, the stroke of the needle-bar being thus varied to regulate the length or size of the loop of each stitch so that said length or size is always appropriate to the thickness of the work through which said loop is drawn upwardly from horn 24 by the needle 25.
- 10 The presser-foot mechanism comprises a vertically disposed presser-bar 26, Fig. 9, slidably mounted within ways provided upon the top and bottom walls of the frame 10, the presser-bar being held within said ways by the front plate 15 10a which is provided upon its rear side with blocks 27 bearing against the front side of the presser-bar.
- At the lower end of the presser-bar is a presser-foot 28, Fig. 7; a work guide including a roll 29 20 for engaging the edge of the sole that is being operated upon, and a feed tongue 30 provided at its lower end with a work-engaging feed point 31.
- Within the box-like head 10 the presser-bar 25 26 is provided with a rigid rearwardly projecting arm 32, Fig. 9, formed with a slot 33 that is occupied by a pin 34 carried by one of the arms of a bell-crank lever 35 fast on the shaft 20 which carries fulcrum arm 19, Fig. 8. The other 30 arm of bell-crank 35 extends upwardly and is formed upon one side thereof with an arcuate groove or slot 36 within which is slidably fitted an arcuate clutch jaw or block 37. The groove or slot 36 is concentric with the axis of shaft 20 35 and its outermost and uppermost side wall 39 is also exteriorly arcuate and concentric with the axis of shaft 20 and slidably mounted upon the exterior of this side wall 39 is another arcuate clutch jaw or block 40.
- 40 The two clutch blocks 37 and 40 are disposed between the arms of a forked clutch lever 41 which embraces said two blocks and also the adjacent arm of bell crank 35. Clutch block 37 is formed at its middle with an aperture that is occupied by a pintle 42 by means of which said block is pivotally connected with the arms of lever 41, the axis of said pintle being parallel with the axis of shaft 20. The clutch block 40 is likewise pivotally connected with the arms of lever 41 by means of a pintle 43 whose axis is also parallel with the axis of shaft 20.
- The pintle 42 has connected with it one end of a coiled spring 44 whose opposite end is fastened at 45 to the frame 10, the anchorage 45 being located so that the tension of said spring 44 yieldingly urges the block 37 longitudinally in one direction with respect to the slot or groove 36.
- The pintle 43 of block 40 is connected by a link 46 with a stud bolt 47 fixed in position with- 60 in an arcuate slot 48 formed in an arm 49 that is part of a rocker 50 loosely mounted upon a stud 51 projecting from frame 10. This slot 48 is concentric with the axis of pintle 43 when bell-crank 35 is at the limit of its movement away from rocker 50.
- 65 The rocker 50 also includes a second arm 52 carrying a roll 53 that occupies a cam groove 54 formed in one face of a gear 55 fast on main shaft 23. This gear acts through the usual mechanism, not shown, to operate the whirl or looper of the horn 24.
- During the operation of the machine the cam groove 54 acts to vibrate the rocker 50 and the latter acts through the link 46 and clutch lever 70 41 to swing bell-crank 35 back and forth on the axis of shaft 20 thereby to slightly raise and lower the presser-bar 26 in timed relation with the vertical movements of the needle-bar 11 and also in timed relation with the feed strokes of the feed tongue 30. These limited movements of the presser-bar 26 during the sewing operation are accompanied by slight displacement of the fulcrum block 17, within slot 16, Fig. 8, but this is negligible.
- As shown in Figs. 1 and 9, the presser-bar 26 10 is made intermediate its ends with a second rigid laterally projecting arm 56 which serves as an abutment seat for one end of a coiled spring 57. The opposite end of this spring is seated against the flange of an abutment member 58 which in turn is seated against the inner end of an abutment screw 59 occupying a threaded aperture provided through the top wall of frame 10. It will be clear that screw 59 may be adjusted to regulate the normal downward pressure of spring 57 on presser-bar 26.
- A block 60, Fig. 9, fastened in position upon the rear side of the upper end portion of the presser-bar 26 serves as a stop which engages the top wall of frame 10 to limit the downward movement of the presser-bar when there is no work upon the horn 24 and bell-crank 35 is at the limit of its movement toward the presser-bar.
- When the clutch lever 41 is pulled toward the right by link 46, Fig. 9, the spring 44 yieldingly restrains the lower end of said lever with the result that the two clutch blocks 37 and 40 grip the arcuate flange 39 of said lever between them thus swinging the bell-crank 35 toward the right, the clutch lever and bell-crank moving in that direction as one. When the bell-crank is thus swung toward the right it acts through the pintle 34 to slightly lift the presser-bar 26 against the pressure of the spring 57, and said presser-bar occupies this elevated position during the time that the feed tongue 30, Fig. 1, is making its work-feeding stroke toward the left. Immediately after the completion of the work-feeding stroke of tongue 30 the bell-crank 35 and clutch lever 41 are swung as one toward the left, Fig. 9, by cam 54 acting through rocker 50 and link 46 until a pin 61 projecting from the exposed side of block 37 engages an adjustable abutment screw 62 on frame 10. Thereafter continued movement of link 46 toward the left swings the clutch lever 41 independently on pintle 42 thereby unclutching blocks 37 and 40 from the arcuate flange 39 and permitting the spring 57 to yieldingly hold the foot of the presser-bar against the work.
- The cam 54 is constructed so that at the conclusion of about two hundred degrees of movement of both cams 54 and 22 from the positions shown in Figs. 8 and 9 the needle-bar is at the limit of its upward movement and the pin 61 is against abutment screw 62. Therefore, at that time the presser-bar is free to be lifted manually, and bell-crank 35 is free to be swung therewith toward the right, Fig. 9, independently of clutch lever 41, to permit the work to be placed in position on the horn 24 or removed therefrom.
- It will also be clear that whatever be the thickness of the work the clutch lever 41 and bell-crank 35 will always cooperate to function as above described, viz., to raise the presser-bar during the feed stroke of tongue 30 and to free the presser-bar so that it can be manually lifted while the needle-bar is at the upper end of its stroke.
- Pivots mounted at 63 upon the exterior of one of the side walls of frame 10 is a lever 64 having a forwardly extending arm provided with

5 a laterally extending end portion occupying a position immediately beneath a vertical plunger 65 slidably mounted within a bearing provided in the bottom wall of the frame. The upper end of this plunger occupies a position immediately beneath the arm 32 of the presser-bar. The lever 64 is also provided with a rearwardly extending arm to the free end of which is connected the upper end of a rod 66 whose lower end is connected with a foot treadle, that is not shown. When this treadle is depressed it acts through rod 66, lever 64 and plunger 65 to raise the presser-bar 26 thereby to permit the work to be placed in position on the horn or to be removed therefrom.

10 When a relatively thin piece of work is upon the horn 24 the presser-bar 26 occupies a correspondingly low position and when a relatively thick piece of work is in position upon the horn the presser-bar occupies a correspondingly high position. Therefore, the two arms 35 and 19 which are fast on shaft 20 and movable as one will be angularly positioned differently by work of different thicknesses while the presser-foot is 15 in engagement with the work. Consequently, the distance between the fulcrum 18 of lever 14, Fig. 8, and the pivotal connection 15 will vary with work of different thicknesses, being comparatively great when the work is thick and comparatively 20 small when the work is thin, and as a result the stroke of the needle-bar will correspond to, and vary with, the thickness of the work so that the loop drawn up by the needle is always of a length that is proportionate and appropriate to the 25 thickness of the work.

30 The cast-off element 67 is a rod or bar of small diameter slidably confined within a longitudinal groove 68, Figs. 2, 3 and 8, formed in the needle-bar 11 at one side thereof. The upper end portion of the cast-off bar occupies a position within a recess formed in one side of the needle-bar as best shown in Fig. 2 and has fixed thereon a head 35 having a flat side fitting against the flat bottom wall 10 of said recess thereby to hold the cast-off bar against rotation within its groove.

35 Directly beneath the head 69 is one arm of a small bell-crank lever 71 fulcrumed at 12 on an arm 13 extending downwardly from and forming part of the collar 12 of the needle-bar. The 40 other arm of bell-crank 71 extends upwardly from fulcrum 12 and is connected by a stiff wire link 14, Figs. 4, 8 and 9, with the lower end of arm 52 of the rocker 50.

45 During the operation of the machine the vibratory movements imparted to rocker 50 act through link 14 and bell-crank 71 to shift the cast-off 67 relatively to the needle-bar, said cast-off being moved in one direction by the bell-crank and in the opposite direction by a wire bow spring 50. One arm of spring 75 bears against the 55 underside of collar 12 and the other arm against the top of the head 69 of the cast-off.

55 During the downward movement of the needle-bar toward the position shown in Fig. 7, the cam 54, Fig. 9, acts through rocker 50, link 14 and bell-crank 71 to hold the cast-off 67 above the hook of needle 25 with the result that as the needle is driven through the work and into the horn 24 where the whirl or looper of the latter 60 lays the thread of the next loop around the same as usual, the preceding loop remaining above the work so that said next loop is pulled through it when the needle moves upwardly.

65 While the needle dwells in its lowest position 75 shown in Fig. 7, the cam 54 swings bell-crank

70 away from the head 69 of the cast-off which permits the bow spring 75 yieldingly to press and hold the cast-off against the work W where it remains until the hook of the needle emerges from the work as the needle-bar is raised.

5

75 During the upward movement of the needle-bar the cast-off covers the hook of the needle but after the arrival of the needle-bar at the limit of its upward movement the cam 54 acts through rocker 50, link 14 and bell-crank 71 to continue 10 the upward movement of the cast-off thereby uncovering the hook of the needle preparatory to the descent of the needle-bar.

15 Thereafter the needle-bar and cast-off descend as one with the hook of the needle uncovered until the parts are again in the positions shown in Fig. 7.

20 The cast-off is an important element in a machine of this class and unless it is operated properly and with certainty to cover and uncover the hook of the needle the machine will not function properly and will cause considerable breakage of thread. Heretofore the cast-off has been actuated and controlled by a friction device which required continually to be adjusted to take up for 25 wear and which required to be particularly adjusted for the particular speed at which the machine was operated.

25 My new cast-off is operated positively by the cam 54 in one direction while its movement in the 30 opposite direction under the influence of the bow spring 75 is also positively controlled by said cam. This mode of operation is wholly new so far as I know.

35 It is also a novel feature of this machine that 35 a single cam-actuated member, such as rocker 50, serves to control and operate both the cast-off and the presser-bar.

40 In my improved machine also, the presser-bar is connected with its actuating and controlling cam through a lever and a friction clutch carried thereby and it is a feature of the invention that at one end of the stroke of this lever the friction clutch, through engagement with a stationary abutment, is unset and that this unsetting of the 45 clutch occurs while the needle-bar is at the end of its upward stroke so that the presser-bar is then free to be manually lifted. The friction clutch remains unset until completion of the 50 downward movement of the needle-bar and then during the upward movement of the needle-bar the friction clutch moves away from the stationary abutment and is thereby automatically set so that it acts through the lever to lift the 55 presser-bar and hold it away from the work while the latter is fed forward for the next stitch.

60 It is a feature of the above described needle-bar operating mechanism that the triangular cam 22 gives the same length of dwell to the needle-bar at the lower end of its stroke whatever be the 60 length of the latter, whereas heretofore this period of dwell was varied when the stroke of the needle was varied to make it appropriate to the thickness of the work being operated upon. That is, heretofore, when the stroke of the needle was 65 increased for thicker work the period of rest during which the looper or whirl of the horn was operated was sometimes shortened to such an extent as to require speeding up the looper. This objectionable feature is obviated by my new needle-bar operating mechanism.

70 It will also be observed that the same lever 35 which carries the friction clutch and through which the presser-bar is operated by cam 54 also 75 serves as the means through which the presser-

bar acts to adjust the needle-bar operating mechanism so as to vary the stroke of the needle-bar when the thickness of the work varies thereby to maintain the length of the loop always proportionate to said thickness.

The feed tongue 30 is slidably and pivotally connected with the usual cam plate 16 fast on presser-bar 26 by means of a bolt 17 which also serves to pivotally connect one end of the usual

link 18 with said tongue. The opposite end of link 18 is pivotally connected at 19, Fig. 1, with one arm of a lever 80 fulcrumed at 81 and having its opposite arm pivotally connected at 82 with an arm 83 fast on a horizontal rockshaft 84, Fig.

15 6. This rockshaft is journaled in bearings provided upon the upper side of the bottom wall of the housing 10 and is also provided with another arm 85 carrying a cam roll 86 that is engaged by a cam 67 on main shaft 23.

20 20 The upper end of the feed tongue 30 co-operates as usual with an abutment pin 88, Fig. 1, carried by presser-bar 26, said upper end being yieldingly urged toward said pin by a spring 89 one end of which is fastened to the feed tongue

25 above bolt 17 and the opposite end to lever 80. Lever 80 is formed with an arcuate slot 90 within which is slidably mounted an apertured block 91 through which the fulcrum pintle 81 extends. Pintle 81 is carried by the arms of a 30 forked bracket 92 rigidly fastened by a screw 93 to the frame 10.

When the feed tongue 30 occupies its retracted position shown in Figure 1 the slot 90 is concentric with the axis of screw 93 and by loosening said screw the fulcrum of lever 80 may be adjusted lengthwise of slot 90 without disturbing the position of the feed tongue. This fulcrum adjustment is made when it is desired to vary the length of the work-feeding stroke of tongue 30.

40 40 The cam 87 acts as heretofore through the connections described to operate the feed tongue 30 in timed relation with the vertical movements of the needle-bar 11 and presser-bar 26.

The pressure of the presser-bar on the work is 45 relieved by cam 54 during the upward movement of the needle-bar and while tongue 30 makes its work-feeding stroke which occurs while the needle-bar is near the limit of its upward movement. The return of the tongue 30 to its normal re-50 tracted position is effected while the needle-bar is at the limit of its upward movement.

The pivot bolt 47, Fig. 9, may be manually adjusted lengthwise of slot 48 as desired or necessary to regulate and determine the action of cam 54 55 on the presser-bar. The slot 48 is made concentric with pintle 43 when the presser-bar occupies its lowermost position so that the only effect of adjusting pivot bolt 47 as described is to vary the height to which the presser-bar is lifted by cam 54 for any given adjusted position of abutment screw 62.

What I claim is:

1. A sewing machine of the class described having, in combination, a work-support; a needle-bar movable toward and from said work support; a power transmitting lever whereof one end is connected with said needle-bar; a cam co-operatively associated with the opposite end of said lever for vibrating the latter thereby to cause the same to reciprocate said needle-bar toward and from said work-support so that it dwells for a period of time at each end of its stroke; a driven shaft on which said cam is mounted, and a shiftable fulcrum for said power-transmitting lever that is adjustable relatively to said lever

5 toward and from said cam so as to vary the length of the stroke of the needle-bar without changing the position occupied by the latter when it is at the limit of its movement toward said work-support and without variation in the length of time said needle-bar dwells at said limit.

2. A sewing machine of the class described having, in combination, a work-support; a presser-bar movable toward and from said work-support; a needle-bar movable toward and from said work-support; a lever connected with said needle-bar; a cam for vibrating said lever thereby to cause the same to reciprocate said needle-bar toward and from said work-support so that it dwells for a period of time at each end of its stroke; a driven shaft on which said cam is mounted; a shiftable fulcrum for said lever that is adjustable relatively to said lever so as to vary the length of stroke of the needle-bar without changing the position occupied by the latter when it is at the limit of its movement toward said work-support and without variation in the length of time said needle-bar dwells at said limit, and means through which said presser-bar acts to adjust and set said fulcrum to cause said lever to 20 impart a length of stroke to said needle-bar that is proportionate and appropriate to the thickness of the work being operated upon as detected by said presser-bar.

3. A sewing machine of the class described having, in combination, a work-support; a needle-bar movable toward and from said work support; a power-transmitting lever connected with said needle-bar; an approximately triangular equilateral cam for vibrating said lever thereby to 35 cause the same to reciprocate said needle-bar toward and from said work-support so that it dwells for a period of time at each end of its stroke; a driven shaft on which said cam is mounted, and a shiftable fulcrum for said power- 40 transmitting lever that is adjustable relatively to said lever toward and from said cam so as to vary the length of the stroke of the needle-bar without changing the position occupied by the latter when it is at the limit of its movement toward 45 said work-support and without variation in the length of time said needle-bar dwells at said limit.

4. A sewing machine of the class described having, in combination, a work-support; a presser-bar movable toward and from said work-support; a needle-bar movable toward and from said work-support; a lever connected with said needle-bar; an approximately triangular equilateral cam for vibrating said lever thereby to cause the same to 55 reciprocate said needle-bar toward and from said work-support so that it dwells for a period of time at each end of its stroke; a driven shaft on which said cam is mounted; a shiftable fulcrum for said lever that is adjustable relatively 60 to said lever so as to vary the length of stroke of the needle-bar without changing the position occupied by the latter when it is at the limit of its movement toward said work-support and without variation in the length of time said needle-bar dwells at said limit, and means through which said presser-bar acts to adjust and set said fulcrum to cause said lever to impart a length of stroke to said needle-bar that is proportionate and appropriate to the thickness of the work 70 being operated upon as detected by said presser-bar.

5. A sewing machine of the character described having, in combination, a work-support; a needle-bar movable toward and from said work- 75

support; a lever having one end thereof connected with said needle-bar, said lever having its opposite end portion provided with a straight longitudinally disposed slot and its intermediate portion formed with a longitudinally disposed arcuate slot; an approximately triangular equilateral cam disposed within said straight slot and continuously in engagement with the opposite sides thereof, said cam being operable to vibrate 5 said lever thereby to cause the same to reciprocate said needle-bar toward and from said work-support so that it dwells for a period of time at each end of its stroke; a driven shaft on which said cam is mounted; an arcuate fulcrum block 10 slidably mounted within said arcuate slot; a fulcrum arm having one end thereof pivotally connected with said block, said fulcrum arm being supported so that it is angularly adjustable on a pivot with respect to which said arcuate slot is 15 concentric when said needle-bar is at the limit of its movement toward said work-support, and means through which the work being operated upon acts to angularly position said fulcrum arm so that the length of the stroke imparted to said 20 needle bar by said lever is proportionate and appropriate to the thickness of said work.

6. A sewing machine of the class described having, in combination, a work-support; a presser-bar movable toward and from said work-support; a needle-bar movable toward and from said work-support; mechanism for positively reciprocating said needle-bar, said mechanism including a power-transmitting lever and a fulcrum for said lever that is adjustable to vary 25 the length of stroke of said needle-bar without change in the position thereof when at the limit of its movement toward said work-support; a movable member through which said presser-bar acts to adjust and set said fulcrum according to 30 the thickness of the work being operated upon; a driven shaft; means operated by said shaft for intermittently feeding the work forward in timed relation with the movements of said needle-bar, and means through which said shaft periodically 35 operates said member thereby to raise said presser-bar while the work is being fed forward.

7. A sewing machine of the character described constructed in accordance with claim 6 wherein said last mentioned means comprises a cam fast 40 on said driven shaft; a clutch device supported by said movable member and shifted bodily back and forth by said cam in timed relation with the operation of said work-feeding means, said device operating, when shifted by said cam in one 45 direction, to grip and adjust said movable member thereby to lift said presser-bar and when shifted by said cam in the opposite direction to adjust said movable member so as to restore said presser-bar to its lowermost position again, and 50 stationarily supported means for engaging said clutch device and maintaining the same unset while the latter is at the limit of its movement in said opposite direction.

8. A sewing machine of the character described having, in combination, a work-support; a presser-bar movable toward and from said work-support; a spring urging said presser-bar toward said work-support; a needle-bar movable toward and from said work-support; mechanism 55 for positively controlling and reciprocating said needle-bar, said mechanism including a lever and a fulcrum for said lever that is adjustable to vary the length of the stroke of said needle-bar without change in the position thereof when at the 60 limit of its movement toward said work-sup-

port; a movable member through which said presser-bar acts to adjust and set said fulcrum according to the thickness of the work being operated upon; a driven shaft; means operated by said shaft for intermittently feeding the work forward in timed relation with the movements of said needle-bar; a clutch device slidably supported by said movable member; means through which said shaft acts to shift said clutch device bodily back and forth in a direction parallel with the path of said movable member and in timed relation with the operation of said needle-bar and said work-feeding means, said device operating when shifted in one direction to grip and adjust said movable member thereby to lift said 10 presser-bar and when shifted in the opposite direction to adjust said movable member so as to restore said presser-bar to its lowermost position again, and stationarily supported means for engaging said clutch device and maintaining the 15 same unset while the latter is at the limit of its movement in said opposite direction.

9. A sewing machine of the class described having, in combination, a work-support; a needle-bar movable endwise toward and from said work-support; a driven shaft; mechanism through which said shaft acts to reciprocate said needle-bar; a cast-off slidably mounted upon said needle-bar; a spring for urging said cast-off toward said work-support; an operating lever for raising said cast-off relatively to said needle-bar, said lever being pivotally mounted upon said needle-bar, and mechanism connecting said member and shaft through which the latter acts to control and actuate said member thereby to adjust said cast-off relatively to said needle-bar in timed relation with respect to the movements of the latter.

10. A sewing machine of the character described having, in combination, a work-support; a needle-bar movable endwise toward and from said work-support; a driven shaft; mechanism through which said shaft acts to reciprocate said needle-bar; a cast-off slidably mounted upon said needle-bar; a spring carried by said needle-bar for urging said cast-off toward said work-support; a bell-crank for operating said cast-off, said bell-crank being pivotally mounted on said needle-bar, and means connecting said bell-crank and shaft through which the latter acts to 40 positively control and actuate said bell-crank thereby to adjust said cast-off relatively to said needle-bar in timed relation with respect to the 45 movements of the latter.

11. A sewing machine of the character described having, in combination, a work-support; a presser-bar movable endwise toward and from said work-support; a spring urging said presser-bar toward said work-support; a needle-bar movable endwise toward and from said work-support; a driven shaft; mechanism through which said shaft acts to reciprocate said needle-bar, said mechanism being adjustable to vary the length of the stroke of said needle-bar; a movable member through which said presser-bar acts to adjust and set said mechanism according to the thickness of the work being operated upon; means operated by said shaft for intermittently feeding the work forward in timed relation with respect to the movements of said needle-bar; a clutch device slidably supported by said movable member; a cam on said driven shaft; a rocker that is actuated by said cam in timed relation with respect to the operation of said work-feeding means; a link through which said 50 55 60 65 70 75

- rocker acts to shift said clutch device bodily back and forth in a direction parallel with the path of said movable member, said device operating when shifted in one direction to grip and adjust said movable member thereby to lift said presser-bar and when shifted in the opposite direction to adjust said movable member so as to restore said presser-bar to its lowermost position again; stationarily supported means for engaging said clutch device and maintaining the same un-set while it is at the limit of its movement in said opposite direction; a cast-off slidably mounted on said needle-bar; a spring urging said cast-off toward said work-support; a bell-crank for operating said cast-off, said bell-crank being pivotally mounted upon said needle-bar, and a link connecting said bell-crank and rocker through which the latter acts to operate the former in timed relation with respect to the movements of the needle-bar.

WALTER PEARSON. 10
